SIDE-SPOUTED CLOSURE FOR DISPENSERS

Jack W. Soffer, St. Louis, Mo., assignor to Development Research, Inc., St. Louis, Mo., a corporation of Missouri

Application October 18, 1954, Serial No. 32,691

Term of patent 14 years

(Cl. D58—26)

FIG. 1

FIG. 2

FIG. 3

Figure 1 is a front elevation of a side-spouted closure for dispensers, embodying my new design;

Figure 2 is a side elevation of said closure; and

Figure 3 is a top elevation thereof.

I claim:

The ornamental design for a side-spouted closure for dispensers, substantially as shown.
